HIGH-FREQUENCY ELECTRON TUBE
STRUCTURE

William W. Hansen and John R. Woodyard, Gar-
den City, N. Y., assignors to The Sperry Cor-
poration, Great Neck, N. Y., a corporation of
Delaware

Original application October 23, 1941, Serial No.
416,170, now Patent No. 2,425,738, dated August
19, 1947. Divided and this application June
20, 1945, Serial No. 600,440

6 Claims. (Cl. 315—6)

1

The present invention is directed to the art including electron discharge devices operating at super-high or microwave frequencies of the order of 300 megacycles per second or higher, corresponding to wavelengths of the order of one meter or shorter. The present invention is more particularly concerned with such devices for multiplying a lower frequency to a value in this super-high frequency range or for multiplying one microwave frequency to form a much higher microwave frequency. The present application is a true division of copending application Serial No. 416,170 for High Frequency Electron Tube Structure, filed October 23, 1941, now Patent No. 2,425,738 granted August 19, 1947.

In U. S. Patent No. 2,281,935 granted May 5, 1942, to William W. Hansen (one of the present applicants herein) and Russell H. Varian, there is disclosed one form of apparatus suitable for generating oscillations of a super-high frequency and also for multiplying this frequency to a still higher harmonic frequency. Such devices operate upon the velocity modulation principle in which the velocities of the electrons of an electron stream are periodically varied at a predetermined frequency. Thereafter the velocity-varied electrons are passed through a field-free drift space in which the faster electrons overtake the slower electrons to form electron groups or bunches, from which, in the case of a frequency multiplier, energy of a frequency harmonically related to the frequency of the velocity variation may be extracted.

Because of practical considerations, such frequency multiplier devices have low beam conversion efficiency and high frequency gain; that is, the output high frequency power forms but a small fraction of the power used to produce the electron stream, and also only a small fraction of the high frequency power supplied to produce the velocity modulation. Ordinarily, therefore, such devices require further amplification of the multiplied frequency wave, such as shown in this Patent No. 2,281,935. Amplifiers for this purpose are generally also of the velocity-modulation type utilizing cavity resonators of the same type as are used in the frequency multiplier device. Such a system of a frequency multiplier feeding a separate amplifier is awkward and cumbersome in operation, since difficulties are experienced in accurately tuning all the many resonators to the proper frequencies and in maintaining these resonators tuned to the proper frequency. Also, such systems are relatively inefficient, since two separate electron streams must be produced, each

2

requiring independent power excitation, and since the increased number of resonators produce increased losses. Systems of the type shown in this patent are also difficult to maintain stabilized in frequency, since changes in operating conditions, such as changes in exciting potentials or in ambient temperatures, cause marked changes in the frequency of the oscillations generated.

The present invention is directed toward improved frequency multiplying apparatus having greatly increased efficiency and more convenient type of operation as compared to such prior art as exemplified by this Hansen and Varian patent. According to one feature of the present invention, the oscillations whose frequency it is desired to multiply are produced independently of the multiplier device. This permits such oscillations to be produced from or controlled by frequency-stabilized sources, such as crystal-controlled oscillators, which may cooperate with frequency multiplier devices of conventional type to produce the wave whose frequency is to be multiplied by the apparatus forming the present invention. This may be termed a "driven" multiplier, as distinguished from an oscillator-multiplier shown in the Hansen and Varian patent.

According to another feature of the present invention, such a driven frequency multiplier is combined in the same device with an amplifier stage, using the same electron stream which serves to perform the frequency-multiplying function, and with a decreased number of tuned circuits requiring tuning alignment or tracking.

According to the present invention, an electron stream is varied in velocity (velocity-modulated) at the fundamental frequency to be multiplied, preferably in response to the output of an independent source of oscillations of this fundamental frequency. These velocity-varied electrons are permitted to become bunched or grouped in the usual velocity-grouping fashion and serve to excite a resonant circuit, preferably of the cavity resonator type, which is tuned substantially to the desired harmonic of the fundamental frequency. Instead of utilizing this resonant circuit to supply the output harmonic frequency energy, it is preferred to leave this resonator "floating," that is, unconnected to any load or source other than the electron stream itself. Such a tuned circuit or cavity resonator reacts upon the electron stream to produce further velocity variation of the electrons thereof and to enhance the amount of bunching at the desired harmonic frequency. As a feature of the present invention, the electron stream having this enhanced

grouping or bunching is thereafter used to excite an output resonant circuit, also preferably of the cavity-resonator type, to which may be coupled any suitable load to be energized at this harmonic frequency. In this way the functions of frequency-multiplying and amplification are combined in the same device, using only one electron stream and requiring only two resonant circuits tuned to the harmonic frequency.

Accordingly, it is an object of the present invention to provide improved super-high-frequency frequency multiplier devices having increased beam conversion efficiencies and increased high frequency gain.

It is another object of the present invention to provide improved frequency-multiplier devices combining an amplifying stage integrally therewith.

It is a further object of the present invention to provide improved frequency multiplier devices of the velocity modulation type using a "floating" harmonically tuned resonator between an input fundamental frequency resonator and an output harmonic frequency resonator.

Further objects and advantages will become apparent from the specification, taken in connection with the accompanying drawing, wherein:

Fig. 1 shows an elevational view of one embodiment of the present invention, partly in longitudinal cross-section.

In the drawing there is shown a cathode 181 of any suitable conventional type. Adjacent the cathode 181 is the entrance grid 182 of the input or buncher resonator 183. A suitable source of unidirectional potential (not shown) is connected between cathode 181 and grid 182 so that the electrons from cathode 181 are projected in the form of a stream through grid 182. Resonator 183 is formed by a rigid cylindrical outer wall 184, a slightly dished rigid end wall 186 carrying grid 182, and a flexible wall 178 illustrated as in the form of an annularly crimped diaphragm, at the center of which is secured a tubular member or drift tube 185 providing the drift space and projecting axially within the cylindrical wall 184 in reentrant fashion. Drift tube 185 carries a second grid 177 closely adjacent to grid 182 and in alignment with the electron stream path. A flange 176 is also secured to drift tube 185 substantially parallel to the dished wall 186 of the resonator. Flange 176 cooperates with wall 186 to provide an effective lumped capacitance, permitting reduction in the physical size of the resonator 183 for the particular chosen fundamental frequency to which it is substantially resonant. Suitable coaxial line coupling arrangements 203 are provided, serving as terminals for supplying fundamental frequency energy to resonator 183.

As is well known, resonator 183 may have its resonant frequency adjusted by adjustment of the gap between grid 177 and flange 176 on the one hand and grid 182 and wall 186 on the other hand. In the present device such adjustment may be effected by adjusting the separation between a flange 189 rigidly connected to cylindrical resonator wall 184 and a second flange 193 rigidly connected to the drift tube 185, such adjustment being effected by adjustment of a plurality of symmetrically disposed tuning screws 188 threaded in flange 189 and abutting or recessed in flange 193.

A second similar resonator 187 is provided at the other end of drift tube 185. This resonator

187 comprises a pair of grids 190 and 192 similar to grids 182, 177 and disposed in the path of the electron stream, grid 190 being mounted in the opposite end of drift tube 185 and grid 192 being mounted in a rigid end wall 200 of resonator 187. The resonator 187 is completed by a rigid cylindrical side wall 202 connected to wall 200 and a flexible end wall 204 connected to drift tube 185, and its resonant frequency may be adjusted by adjusting the separation between flange 193 and a further flange 197 rigidly connected to the cylindrical wall 202, as by means of a similar plurality of tuning adjustment screws 188' threaded in flange 197 and bearing on flange 193. In this way resonator 187 may be tuned to the desired harmonic of the fundamental frequency energy supplied to resonator 183.

Resonator 187 may also be supplied with coaxial line terminals 203', mainly for use in accurately tuning resonator 187. These terminals 203' are preferably not used during operation of the device, although, when desired, small amounts of harmonic frequency energy may be usefully supplied thereby to a desired load.

Connected to wall 200 and grid 192 is a further drift tube 185' at whose opposite end is mounted a resonator 195 similar in construction to resonator 187, and having a pair of grids in the electron stream path, similar to grids 190, 192. This resonator 195 may also be tuned by means of the tuning adjustment screws 188'' which serve, through the flanges 199 and 198, to adjust the separation of the grids of resonator 195 in a fashion similar to that of resonator 187. Resonator 195 is tuned to the same harmonic frequency as resonator 187 and is provided with a pair of coaxial line output terminals 197 for supplying the harmonic frequency energy extracted from the electron stream by resonator 195 to the desired load. The electron stream, after passing through the grids of resonator 195, passes through a further tubular member 185'' to a collector indicated at 201 to which the electrons give up their remaining energy.

In operation, the fundamental frequency energy derived from any desirable source, such as a crystal-controlled oscillator and conventional frequency-multiplier chain, is coupled to resonator 183 by one of its terminals 203, resonator 183 being tuned substantially to this fundamental frequency. In this manner a standing electromagnetic field is produced within resonator 183 having a strong alternating electric field component of the fundamental frequency extending axially of the stream between the grids 182 and 177. This alternating electric field component alternately accelerates and decelerates the electrons of the stream and thus velocity-modulates them. These velocity-modulated electrons pass through the field-free drift space defined by drift tube 185 and become at least partially bunched by the time they arrive at the gap between grids 190 and 192 of resonator 187. Resonator 187, which may be termed a "floating" resonator, since ordinarily it is not connected to any load or other source, is tuned to the harmonic of the input fundamental frequency which it is desired to produce. The partially bunched electron stream contains a current component of the fundamental frequency and also components of many harmonics of the fundamental frequency, the desired harmonic to which resonator 187 is tuned.

In this way the electron stream excites resonator 187 to oscillate at this desired harmonic

frequency, thereby producing an axial alternating electric field component of this harmonic frequency between grids 190 and 192. This harmonic electric field further velocity-modulates the electrons of the stream so that after their subsequent passage through the further drift space defined by drift tube 185', the desired harmonic frequency energy content of the electron stream is enriched by the time these electrons arrive at the corresponding grids of resonator 195. In this way greatly increased amounts of harmonic frequency energy are supplied to resonator 195 by the electron stream and are available to be supplied to any load coupled to the concentric transmission line terminals 197.

In effect, resonators 183 and 187 coupled by drift tube 185 form a driven frequency multiplier, while resonators 187 and 195 coupled by drift tube 185' form a harmonic frequency amplifier. Since these multiplying and amplifying stages utilize the same electron stream, no additional power is needed for amplification over that required for frequency multiplication, so that for the same amount of input beam power and input fundamental frequency power, greatly increased amounts of high frequency energy can be derived from the output resonator 195 over equivalent prior art systems. In this way we have provided for a much simpler and much more highly efficient device for producing frequency multiplication at super-high frequencies.

It is to be noted that such a system, in addition to the advantage (over the prior art system of Patent No. 2,281,935) of reducing the number of harmonic frequency resonant circuits to be tuned and maintained in alignment, has the further advantage with respect to a separate multiplier and amplifier system such as shown in the above-mentioned patent, in that the last resonator of the multiplier of this patent being coupled to the first resonator of the amplifier and being loaded thereby, necessarily has a lower effective shunt impedance than is the case of the floating resonator 187 or the output resonator 195 of the present invention. This increased shunt impedance of the resonators of the present invention causes a much improved amplifying action further tending to increase the output and efficiency.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. Frequency-multiplying and amplifying apparatus comprising means for producing an electron stream, a first cavity resonator having a pair of electron-permeable grids forming portions of the walls thereof and positioned in alignment with the path of said stream, said first resonator being tuned substantially to the fundamental frequency to be multiplied, a drift tube surrounding said stream path beyond said grids, a second cavity resonator having a pair of electron-permeable grids forming portions of the walls thereof and positioned in alignment

55 70

with the path of said stream beyond said drift tube, said second cavity resonator being floating and tuned substantially to a desired harmonic of said fundamental frequency, a second drift tube surrounding said stream path beyond said second resonator, and an output cavity resonator having a pair of electron-permeable grids forming portions of the walls thereof and positioned in alignment with said stream path beyond said second drift tube, said output resonator being also tuned substantially to said harmonic frequency.

2. Frequency-multiplying apparatus comprising means for producing an electron stream, a first cavity resonator along the path of said stream and tuned substantially to a fundamental frequency to be multiplied, a second floating cavity resonator positioned along said stream path spaced from said first resonator and tuned substantially to a harmonic of said fundamental frequency, and a third cavity resonator along said stream path beyond said second resonator and also tuned substantially to said harmonic frequency.

25 30 35 40 45

3. A frequency multiplier electron discharge tube comprising a source of electrons, means for forming said electrons into a stream, means positioned in alignment with the path of said stream consisting of a single apparatus tuned to a predetermined frequency for causing said electrons to form recurrent bunches, means positioned in alignment along the path of said stream comprising a cavity resonator tuned to a harmonic of said frequency for extracting energy from said bunched electrons, and a further cavity resonator means tuned to said harmonic frequency and coupled to said stream for further extracting energy from said stream.

4. Frequency-multiplying apparatus comprising means for producing an electron stream, three pairs of closely spaced electron-permeable grids positioned in spaced relation in alignment with the path of said stream, a fundamental frequency tuned circuit coupled to one of said pairs and having an input terminal coupled thereto, a pair of harmonic frequency tuned circuits coupled respectively to the others of said grid pairs, and an output terminal coupled to one of said harmonic frequency circuits.

5. Apparatus as in claim 4 wherein the other of said harmonic frequency circuits is floating.

6. Apparatus as in claim 4 including a further output terminal coupled to the other of said harmonic frequency circuits.
